UNITED STATES PATENT OFFICE

ABE O. SAMUELS, OF ROCHESTER, NEW YORK, ASSIGNOR TO SAMSON-UNITED CORPORATION, OF ROCHESTER, NEW YORK

DESIGN FOR AN ELECTRIC EGG COOKER

Application filed July 22, 1931. Serial No. 40,634. Term of patent 7 years.

To all whom it may concern:

Be it known that I, ABE O. SAMUELS, a citizen of the United States, residing at Rochester, in the county of Monroe and State of New York, have invented a new, original, and ornamental Design for an Electric Egg Cooker, of which the following is a specification, reference being had to the accompanying drawings, forming a part thereof.

Figure 1 is a top plan view of the electric egg cooker, showing my new design.

Figure 2 is a side elevation of the electric egg cooker.

I claim:

The ornamental design for an electric egg cooker, as shown.

ABE O. SAMUELS.
